UNITED STATES PATENT OFFICE.

TRAUGOTT GOLDE, OF GERA, GERMANY.

TOP FOR CONVEYANCES.

1,190,751.

Specification of Letters Patent. Patented July 11, 1916.

Application filed September 30, 1913. Serial No. 792,567.

To all whom it may concern:

Be it known that I, TRAUGOTT GOLDE, a subject of the German Emperor, residing at Gera, Reuss, Germany, have invented an Improved Vehicle-Top, of which the following is a specification.

This invention relates to a novel top for vehicles which is so constructed, that when folded into its open position it is thrown somewhat forward, so as not to unduly project rearwardly beyond the vehicle body.

In the accompanying drawings: Figure 1 is a side view of a top embodying my invention showing it folded back; Fig. 2 a similar view showing it folded forward.

In carrying out my invention, I make the main back bow *b*, of articulated form, it being composed of an upper section adapted to engage the top-covering and a pair of straight lower sections which are secured to the upper section by stop joints *k* that permit the contiguous ends of the members to swing forwardly. These lower sections are pivotally secured to the vehicle body *a* at their lower ends, and are so jointed to the upper section, that in the unfolded position of the bow they form obtuse angles therewith (Fig. 2). When however, the bow is folded or opened up, the joints *k* will be thrown forward (Fig. 1) so that the bow is correspondingly shortened, and the cover carried by the bow is correspondingly advanced, so as to draw the back of the top into substantial alinement with the back of the vehicle body. To main bow *b*, there are secured a pair of auxiliary back bows, *c*, *d*, and also arms *h* carrying a bow *e*, and arms

g carrying an outrigger bow *f*, which however do not form part of the present invention.

A lever *l* pivoted at its top to the upper section of bow *b*, somewhat above hinge *k*, and at its lower end to the vehicle body, constitutes a brace or guide for the top during the folding and unfolding operation. 45 This lever is hingeless and in the folded position of the top is brought into axial alinement with the body of the upper section of bow *b*, so that the upper portion of the lever will overlap the lower portion of 50 said upper bow section.

I claim:

A vehicle top comprising an articulated bow having an upper section adapted to support a covering, a pair of lower sections pivoted at their lower ends to the vehicle body, stop hinges between the upper section and the lower sections, said lower sections being adapted to form obtuse angles at said hinges with said upper section, during 60 the unfolded position of the top, and bracing members pivoted at their upper ends to said upper section a distance below the upper end thereof, and at their lower ends to the vehicle body, said bracing members being adapted to be axially alined with said upper section during said unfolded position. 65

In testimony whereof I affix my signature in the presence of two witnesses.

TRAUGOTT GOLDE.
